UNITED STATES PATENT OFFICE.

DOD HASLUP, OF GRAFTON, WEST VIRGINIA.

DESIGN FOR A NECKTIE-HOLDER.

SPECIFICATION forming part of Design No. 30,701, dated May 2, 1899.

Application filed March 11, 1899. Serial No. 708,781. Term of patent 14 years.

To all whom it may concern:

Be it known that I, DOD HASLUP, a citizen of the United States, residing at Grafton, in the county of Taylor and State of West Virginia, have invented and produced a new and useful Design for a Necktie-Holder, of which the following is a specification, reference being had to the drawing, in which the figure is a detail perspective view illustrating my invention.

The essential feature of my design consists in its peculiarities of shape, which will be fully set forth hereinafter and pointed out in the claim.

In constructing a necktie-holder in accordance with my design I employ a flat plate A, having tapering sides A' and essentially semi-circular-shaped upper ends A² and an essen-

tially rectangular-shaped tongue A³ at the lower end, which is curved back, as at A⁴, and rests essentially parallel with the body of the plate, the extreme end of the said tongue having rounded corners and bent away from the plate, as shown at A⁵. A series of circular apertures A⁶ are produced in the plate adjacent to the edges thereof.

Having thus fully described my invention, what I claim as new, and desire to secure by Letters Patent of the United States, is—

The design for a necktie-holder, substantially as herein shown and described.

DOD HASLUP.
